UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

CHANNERER.

1,363,004.

Specification of Letters Patent. Patented Dec. 21, 1920.

Application filed March 9, 1916. Serial No. 83,131.

To all whom it may concern:

Be it known that I, HENRY H. MERCER, a citizen of the United States, residing at Claremont, in the county of Sullivan and State of New Hampshire, have invented certain new and useful Improvements in Channelers, of which the following is a full, clear, and exact specification.

My invention relates to channelers.

0 It has among its objects to supply water to a channeler in an improved manner whereby both delays and the necessity for the employment of additional labor are rendered unnecessary so that the channeler 15 may operate more nearly at its maximum efficiency and at smaller expense. A further object of my invention is to provide improved means whereby water may be supplied to a channeler in any position of 20 the latter as it moves back and forth on its track and during such movement of the same, and whereby the time and amount of water flow to the boiler tank thereof may be automatically controlled. A still further 25 object of my invention is to provide improved means for maintaining a water-feeding member or hose under proper tension at all times as the channeler moves back and forth at its work. These and other 30 objects of my invention will hereinafter appear.

In the accompanying drawings, I have, for purpose of illustration, shown one embodiment which my invention may assume 35 in practice, illustrating the same as used in connection with a standard form of channeler, although it is to be understood that the invention is adapted to use in connection with channelers of other types than that 40 shown.

In these drawings,—

Figure 1 is a side elevation of a channeler mounted on its truck and equipped with my improvement.

45 Fig. 2 is a plan view of the water-feeding mechanism, the cover of the driving mechanism therefor being removed to facilitate illustration, and portions of the channeler being omitted for a similar purpose.

50 Fig. 3 is a transverse vertical sectional view through the water-feeding mechanism.

Fig. 4 is a detail sectional view on line 4—4 of Fig. 2.

Fig. 5 is a detail partial sectional view of a portion of the driving mechanism connected to the propulsion motor. 55

Fig. 6 is a detail sectional view on line 6—6 of Fig. 2.

The channeler shown includes a truck 1 provided with axles 2 carrying wheels 3 and movable on these wheels back and forth upon the usual channeler track 4 by a propulsion motor or engine 5 of any desired form. This truck 1 carries at one side of the same a trunnion bar 6 upon which is adjustably mounted a channeler standard 7 carrying one or more chopping engines 8 connected to a channeler gang or gangs 9, the chopping engine or engines being supplied with steam through a pipe 10 from a 70 boiler 11 carried on the truck, and the propulsion motor preferably being similarly supplied from the same source through similar constructions not shown. As illustrated, a water tank 12 is mounted at the 75 side of the boiler 11 and supplied with water in a manner hereinafter described, through a hose 13 attached to a suitable source of supply (not shown) and wound on a reel 14, the latter being connected to 80 the propulsion engine 5 in an improved manner likewise hereinafter described and also being connectible, to a reversible shaft 15 driven by the propulsion engine 5 and having its direction of rotation controlled 85 in a well known manner, the connection to the propulsion engine being such that as the channeler is moved along the track in either direction, the hose is automatically maintained at the proper tension. 90

It will be noted that a pair of injector pipes 16 and 17 extends into the tank 12 and that these pipes are in turn connected to injectors 18 and 19, of well known construction, which cause the water in the tank 95 to be supplied to the bottom of the boiler 11 through pipes 20 and 21 when steam is supplied to the injectors through a suitable pipe 22 connected to the steam dome 23 of the boiler. As shown, the supply of steam 100 to the injector 18 is controlled by a valve 24, while the supply of steam to the injector 19 is controlled by a valve 25, the supply of steam from the steam dome 23 being controlled by a single valve 26. From 105 this, it will be apparent that the water in

the tank 12 will be forced into the boiler through the action of the injectors, all in a well known manner.

Water is supplied to the tank 12 through 5 a vertical pipe 27 and a transversely disposed pipe 28, the latter being controlled by a suitable valve 29 and connected at its outer end with a downwardly extending pipe 30, which is connected through an elbow 31 10 with a pipe 32 extending through the hub 33 of the reel 14. As shown, a spring 34 is coiled about the outer end of this pipe 32 and disposed between a flange portion 35 on the elbow 31 and a flange 36 on a sleeve 15 37 which incloses the pipe 32 and has its inner end held by the spring 34 in engagement with an annular flange 38 on the inner end of the pipe. As shown, this member 37 is also in turn inclosed within an extension 39 formed integral with, but of greater internal diameter than, a tubular shaft 40 which extends between the tank 12 and boiler 11 and is journaled at its opposite ends in upstanding brackets 41 and 42 bolted 20 on the truck 1, one of which carries a support 43 for the pipe 28. Fixed to this shaft extension 39 by a bolt 44, is another sleeve member 45 which carries the reel hub 33, the bolt 44 also acting to clamp this hub 0 in position. As illustrated, a plug 46 is inserted in the pipe 40 adjacent the inner end of the pipe 32, and a threaded nipple 47 on one end of the hose 13, is threaded into a suitable port 48 formed in the members 39 35 and 45 at a point between the plug and the end of the pipe 32.

In order that water may be supplied to the channeler in any position of the same and as the channeler moves back and forth 40 along its track 4, I have provided a connection between the reel 14 and the propulsion engine 5 including a driving member 45 preferably carried on the reversible shaft 15 driven from the propulsion engine 5. As 45 shown, this shaft 15 is connected in the usual manner to one of the axles 2 through a worm 49 and worm gear 50, it being understood that its opposite end is preferably similarly connected to the other axle. Rotatably mounted on this shaft and located 50 at a point intermediate the ends of the shaft is a gear 51 which meshes with a second gear 52 carried upon an upper shaft 53, which is disposed at right angles to the shaft 40 and likewise journaled in the bracket 42. Upon the opposite end of this shaft 53 is also carried a worm 54 meshing with a worm gear 55 which is loosely mounted upon the adjacent end of the shaft 40 and connectable thereto by means of friction members 56 and 57, splined to the shaft 40 on opposite sides of the gear 55 and controllable by an adjusting screw 58. As shown, this screw is threaded in the end of the shaft 65 and acts through washers 59 and 60 and an

intermediate coiled spring 61, to vary the pressure of the members 56 and 57 upon opposite sides of the member 55. Obviously when the gear 51 is rotated through its connection to the propulsion engine 5, herein-after described, the rotation of the same will, through the connection just described, cause a rotation of the shaft 40 and thereby cause the reel 14 to be operated to wind up the hose 13 thereon, and the reel, due to the provision of its slip connection 56, 57, will remain free at all times to unwind under the pull of the hose when the channeler is moved in an opposite direction.

In order to maintain any desired water level in the tank 12, I have provided a float 62 connected through a rod 63 to a conical valve member 64 having one or more ports 65 therein adapted to register in certain positions of the same with one or more ports 66 in a conical seat 67 which is screw-threaded at 68 into a chamber 69 carried on the end of the pipe 27. As shown, this conical valve member 64 is also provided with bearings 70 in the member 69 and is provided with an extension 71 on its front end extending through a sleeve 72 on the member 67 and having an opening 73 therein, through which the rod 63 extends, the latter being adjustably connected to the extension 71 by means of a set-screw 74. Obviously, through this construction, the water level in the tank 12 may be maintained at any desired point, the float 62 acting automatically to open or cut off the supply of water 100 when the latter has reached any desired minimum or maximum level in the tank.

It will also be noted that I have provided means whereby the reel may be disconnected from the propulsion engine 5 when desired. One of these means includes clamping members 75 and 76 formed on the bracket 42 and inclosing the shaft 53, for which they form a journal, these members being adjustable into or out of their journal relation with 105 this shaft by means of a bolt connection 78. When the mechanism is at rest and this connection 78 is loosened, the gear 52 may be forced manually to the right (Fig. 4) and out of mesh with the gear 51 in such a manner as thereby to disconnect the reel from the propulsion engine. Obviously, if desired, the gear 52 may then be locked in this inoperative position by simply reclamping the bolt connection 78, and may be returned 110 to operative position by a simple reversal of the process above described. When it is desired to return the gear 52 to mesh with the gear 51, it will also be noted that this may be accomplished after the release of the 115 bolt connection 78, by rotation of the reel 14 in such a manner as to cause the gear 55 to feed the worm 54 upwardly and thereby bring the gears into the desired meshing 120 relation. Here it should also be observed 130

- that due to the fact that the gear 55 rotates always in the same direction, the normal tendency of the same when in operation is to maintain the gear 52 in its outer or operative position with respect to the gear 51. In order to disconnect the reel by the means above described, it will be noted that it is necessary for the mechanism to be at rest. However, if at any time it is desired to disconnect the reel while the mechanism is working, this may obviously be readily accomplished by adjusting the bolt 58 in such a manner as to release the driving connection.
- Attention should also be directed to the fact that in my improved construction, the friction clutch connection for the reel-driving shaft is inclosed within a suitable oil-tight casing 79 provided with a cover 80 and adapted to contain oil so that all the parts may run in oil, an oil inlet plug 81 being conveniently located in this cover. It will also be noted that the shaft 40 is likewise provided with suitable lubricating means at 82, and that a suitable oil-tight chamber 83 is provided for the worm and worm gear 49, 50, this chamber 83 also being accessible for filling, through a conveniently located inlet 84. Attention is also directed to the fact that to facilitate assembly and removal of the driving parts, the worm 49 is journaled at one end in a threaded removable thrust bearing member 85, threaded into an up-standing part 86 on the bracket 42 and clamped by suitable bolts 87, and that the worm shaft 53 is bodily removable through an opening normally closed by a threaded plug 88. In connection with the detail of the tank, it will also be noted that the same may be drained whenever desired by removing a threaded plug 89 in its bottom.
- The reversing connections for the shaft 15 may assume any desired form, and are preferably connected between the opposite ends of the same and the propulsion engine shaft, in a well known manner, so that as these connections are reversed, the shaft 15 may drive the truck 2 in either direction. In Fig. 5, I have shown one of these clutch connections, and improved means whereby the gear 51 is rotated continuously in one direction by the propulsion engine 5 irrespective of the direction of rotation of the shaft 15. These connections, as shown, include a pinion 90 carried on the propulsion engine shaft 91 and meshing with an internal gear 92 having a casing 93 preferably fixed to and rotatable with the gear 51, both the internal gear 92 and the gear 51 being freely rotatable about the shaft 15 and continuously rotated by the engine shaft 91. Disposed within the gear casing 93, is the means for connecting the shaft 15 to the engine shaft 91 and driving the shaft 15 in one direction. As shown, this means includes the driven member 94 of a standard form of band clutch having its hub 95 splined to the shaft 15 and extending through the gear 51, and its periphery surrounded by a friction band 96 which is in turn controlled by its usual dog 97, journaled in the casing 93 and having an operating arm 98 extending into the path of a suitable manually adjustable clutch shipping member 99, which is reciprocable along the shaft.
- In the operation of my improved mechanism, while the channeler remains stationary water will obviously be supplied to the tank 12 through the hose 13 and pipes 30, 28, and 27, and will be maintained at the desired level in the tank by the action of the float 62 and its controlled valve 64. The water will, of course, also be withdrawn from the tank 12 for use in the boiler 11 as required, by the action of the steam passing through the pipe 22 to the injectors 18 and 19. When the propulsion engine 5 is connected to the shaft 15, however, in such a manner as to rotate the latter and thereby the axles 2 to move the truck along the track 4 in a direction away from the source of water supply, it will be noted that the pull of the hose will rotate the reel in such a manner as to unreel the needed amount of hose for a given movement of the channeler, the reel through its slip clutch connection being free to move independently of the constantly rotating worm gear 55 which is always tending to wind up the reel. When the direction of travel of the channeler is reversed, it will also be noted that due to the action of this member 55 and its coöperating friction members 56 and 57, the reel will obviously be rotated in the opposite direction, and thus during the reverse movement of the channeler likewise maintain the proper tension on the hose. It will of course also be obvious that by suitably proportioning the speed of rotation of the several parts and particularly of the member 55, the usual disturbing element of variation arising from the variation in the diameter of the reel may be effectually neutralized. Attention should also be directed to the fact that when desired the bolt connection 78 may be withdrawn in order to let the gear 52 be withdrawn from engagement with the gear 51, and the bolt connection then tightened, whereupon it will be noted that the reel may be turned into any desired position by hand or otherwise, and will be held in any position to which it is adjusted. These and other advantages of my improved construction will, however, be apparent to those skilled in the art.
- While I have in this application specifically described one embodiment which my invention may assume in practice, it is of course to be understood that this form of the same is used for purposes of illustration, and that the invention itself may be modified and embodied in various other forms without de-

parting from its spirit, it being my intention to include all such forms within the scope of the appended claims.

What I claim as new and desire to secure by Letters Patent is:

1. In a channeler, a truck, a fluid pressure channeler mechanism thereon including a fluid pressure generator and mechanism operated by fluid pressure to reciprocate said truck during the channeling operation, a stationary source of liquid for transformation in said fluid pressure generator, a connection between said generator and said source, and means for maintaining said connection at all times free from slack.
2. In a channeler, a truck, steam channeler mechanism thereon including a boiler, mechanism for reciprocating said truck during the channeling operation, and means for maintaining a constant fluid supply for said boiler during said operation.
3. In a channeler, a truck, steam channeler mechanism thereon including a boiler, mechanism for reciprocating said truck during the channeling operation, and means including a hose and hose reel operatively connected to said mechanism for maintaining a constant fluid supply for said boiler during said operation.
4. In combination, a truck, truck driving mechanism comprising a unidirectional prime mover, a reel, reversible connections between said prime mover and said truck driving mechanism, and a non-positive direct driving connection between said prime mover and said reel driving mechanism.
5. In combination, a movable truck, truck driving means including an engine rotatable in the same direction for driving the truck backward or forward and a reversing mechanism, a reel carried by said truck, and reel driving means driven in one direction by said engine independent of the direction of movement of said truck.
6. In combination, a movable truck, truck driving means including an engine rotatable in the same direction for driving the truck backward or forward and a reversing mechanism, a reel carried by said truck, and reel driving means driven in one direction by said engine independent of the direction of movement of said truck and including a non-positive driving mechanism.
7. In combination, a movable support, a member movable therewith and driven in the same direction independent of the direction of movement of said support, a reel, and a reel driving member engaging said first named member and movable in the same direction therewith when the support is moved in one direction, and movable in the opposite direction from said first named member when the support is moved in another direction.
8. In combination, a movable truck, a working unit including a tank carried by said truck, means for supplying fluid to said tank, and means for maintaining said supply means in a predetermined operative relationship with said truck throughout the movement of said truck.
9. In combination, a track, a truck movable thereon, means for propelling said truck back and forth on said track, a working unit carried on said truck, a boiler on said truck supplying power for said unit, means for supplying fluid to said boiler and means for maintaining a predetermined operative relationship between said supplying means and truck throughout the movement of said truck.
10. In combination, a track, a truck movable thereon, means for propelling said truck back and forth on said track, a working unit carried on said truck, a boiler on said truck supplying power for said unit, a tank connected to said boiler, means for supplying fluid to said tank and means for maintaining a predetermined operative relationship between said supplying means and truck throughout the movement of said truck.
11. In combination, a track, a truck movable along the same, an engine on said truck, a boiler on said truck connected with said engine, a tank on said truck connected with said boiler, means for supplying fluid to said tank and means for maintaining a predetermined operative relationship between said supplying means and truck as said truck is moved along said track.
12. In combination, a movable truck, a working unit including a boiler carried by said truck, means including a fluid supply member for maintaining a constant supply of fluid for said boiler, and means for maintaining said supply means in a predetermined operative relationship with said truck throughout the movement of said truck.
13. In combination, a track, a channeler truck thereon, an engine on said truck, a boiler on said truck connected with said engine, means for propelling said truck back and forth on said track, means including a fluid supply member for maintaining a constant supply of fluid to said boiler, and means for maintaining a predetermined operative relationship between said supply member and truck as said truck is moved back and forth.
14. In combination, a track, a truck thereon, a propulsion engine connected to said truck, a boiler on said truck connected with said engine, means for supplying fluid to said boiler, and means operated by said engine for maintaining a predetermined operative relationship between said supplying means and truck as said truck is moved along said track.
15. In combination, a track, a truck thereon, an engine carried by said truck, a boiler

on said truck connected with said engine, and means operatively connected to said engine for supplying fluid to said boiler as said truck is moved along said track.

5 16. In combination, a track, a truck thereon, an engine carried by said truck, a boiler on said truck connected with said engine, a tank on said truck connected with said boiler, and means operatively connected to 10 said engine for supplying fluid to said tank as said truck is moved along said track.

17. In combination, a track, a truck thereon, a propulsion engine, operative connections between the same and said truck for 15 propelling the same in opposite directions, a boiler on said truck connected with said engine, and means operatively connected to said propulsion engine for supplying fluid to said boiler as said truck is moved back 20 and forth.

18. In combination, a movable truck, a working unit carried by said truck, a hose for conducting a liquid to said truck, means on said truck for transforming said liquid 25 to an operating medium for said working unit, and means for automatically keeping said hose substantially taut throughout the movement of said truck.

19. In combination, a movable truck, a working unit carried by said truck, a hose for conducting a liquid to said truck, means on said truck for transforming said liquid into a working medium for said working unit, a reel for said hose, and means for 35 actuating said reel to keep said hose substantially taut throughout the movement of said truck.

20. In combination, a track, a truck movable along the same, an engine mounted on 40 said truck, an engine boiler connected thereto, a boiler tank connected therewith, a reel carried on said truck, a hose carried on said reel and delivering fluid to said tank, and means for propelling said reel from said 45 truck.

21. In combination, a track, a truck movable along the same, a boiler on said truck, a propulsion engine on said truck connected with said boiler, a tank connected to said 50 boiler, a reel operatively connected to said propulsion engine, and a hose carried on said reel delivering fluid to said tank.

22. In combination, a track, a truck movable along the same, a boiler on said truck, a 55 boiler tank on said truck, means for supplying fluid to said boiler tank, means for maintaining a predetermined operative relationship between said supplying means and truck in any position of said truck on said 60 track, and means for automatically maintaining a predetermined fluid level in said tank.

23. In combination, a track, a truck thereon, a propulsion engine connected to said 65 truck, a boiler on said truck connected with

said engine, a boiler tank on said truck, means operated by said engine for supplying fluid to said boiler tank in any position of said truck on said track, and means for automatically maintaining a predetermined 70 fluid level in said tank.

24. In combination, a track, a motor-propelled truck thereon, a boiler on said truck, a boiler tank on said truck, injector water-feeding mechanism connected to said boiler 75 and extending into said tank, means for supplying fluid to said tank, means for maintaining a predetermined operative relationship between said supplying means and truck as said truck is moved along said track, 80 and controlling means for said fluid-supplying means controlled by the level of the fluid in said tank.

25. In combination, a track, a channeler truck thereon, a propulsion engine on said 85 truck, a boiler on said truck connected with said engine, a reel on said truck, a tank on said truck connected to said boiler, a hose on said reel supplying fluid to said tank, and means for connecting and disconnecting 90 said propulsion engine and reel when desired.

26. In combination, a track, a wheel truck mounted thereon having a rotatable axle, a propulsion motor on said truck, a rotatable 95 shaft operatively connected thereto, worm gearing between said shaft and axle, a supplementary shaft disposed above said first mentioned shaft and oppositely connected thereto, a third shaft disposed at right angles 100 to said second shaft, and worm gearing between said last mentioned shafts.

27. In combination, a track, a wheel truck mounted thereon having a rotatable axle, a propulsion motor on said truck, a rotatable 105 shaft operatively connected thereto, worm gearing between said shaft and axle, a supplementary shaft disposed above said first mentioned shaft and operatively connected thereto, a third shaft disposed at right angles 110 to said second shaft, worm gearing between said last mentioned shafts, and a frictional driving connection controlling the connection of said worm gearing to one of said shafts.

28. In combination, a track, a truck thereon, a propulsion engine on said truck, a boiler on said truck connected with said engine, a reel on said truck, a tank on said truck connected to said boiler, a hose on said reel supplying fluid to said tank, and operating means including a frictional driving connection between said reel and said propulsion engine.

29. In a channeling machine, a truck, a 125 propulsion engine mounted thereon, a boiler mounted on said truck and connected to said engine, a tank on said truck connected to said boiler, a shaft connected to said propulsion engine, a reel mounted on said truck 130

and having a rotatable shaft, driving means including gearing between said shaft and the shaft connected to said propulsion engine, and a hose carried on said reel and supplying fluid to said tank.

30. In a channeling machine, a truck, a propulsion engine mounted thereon, a boiler mounted on said truck and connected to said engine, a tank on said truck connected to 10 said boiler, a shaft connected to said propulsion engine, a reel mounted on said truck and having a rotatable shaft, driving means between said shaft and the shaft connected to said propulsion engine including gearing 15 and a coöperating frictional driving connection, and a hose carried on said reel and supplying fluid to said tank.

31. In combination, a track, a truck thereon, a propulsion engine on said truck, a 20 boiler on said truck connected with said engine, a boiler tank on said truck connected with said boiler, a reel on said truck, operative connections between the same and said propulsion engine, a hose on said reel, fluid- 25 conveying means between said hose and tank, a valve on said conveying means, and a float carried in said tank operatively connected to said valve.

32. In a channeling machine, a truck, a propulsion engine mounted thereon, a boiler 30 mounted on said truck and connected to said engine, a tank on said truck connected to said boiler, a shaft connected to said propulsion engine, a reel mounted on said truck and having a rotatable shaft, power connections 35 between said shaft and the shaft connected to said propulsion engine including a worm and worm gear and a frictional driving connection controlling the rotation of one of said shafts, and a hose carried on 40 said reel and supplying fluid to said tank.

33. A truck, running gear therefor, driving means adapted to coöperate with said running gear, a reversible connection between said driving means and said running gear whereby said truck may run in opposite directions, means for supplying said driving means with power comprising a stationary supply means, a flexible connection between said stationary supply and said 50 driving means, and a reel having a direct frictional connection with said driving means.

In testimony whereof I affix my signature.

HENRY H. MERCER.

It is hereby certified that in Letters Patent No. 1,363,004, granted December 21, 1920, upon the application of Henry H. Mercer, of Claremont, New Hampshire, for an improvement in "Channelers," errors appear in the printed specification requiring correction as follows: Page 4, lines 88-97, claims 10-11, after the word "tank" insert a comma; page 5, line 99, claim 26, for the word "oppositely" read *operatively*; and that the said Letters Patent should be read with these corrections therein that the same may conform to the record of the case in the Patent Office.

Signed and sealed this 25th day of January, A. D., 1921.

[SEAL.]

L. B. MANN,

Acting Commissioner of Patents.

Cl. 262-15.
